UNITED STATES PATENT OFFICE.

JOHN DARLING, OF GLASGOW, COUNTY OF LANARK, SCOTLAND.

CAR-COUPLING.

SPECIFICATION forming part of Letters Patent No. 338,041, dated March 16, 1886.

Application filed October 19, 1885. Serial No. 180,329. (No model.)

To all whom it may concern:

Be it known that I, JOHN DARLING, of 11 Bothwell Street, Glasgow, in the county of Lanark, Scotland, engineer, have invented 5 Improvements in Apparatus for Coupling and Uncoupling Railway-Vehicles, of which the following is a specification.

This invention, which relates to improvements in apparatus for coupling and uncoupling railway-vehicles, consists in providing the outer link of the coupling-chain with guides at each side of its outer end, which, when two railway-vehicles are run together, direct the outer end, so as to cause it to slide 10 up over an inclined tail-piece formed on the draw-hook of the opposite vehicle, so that the coupling-chain is thus directed to catch into the coupling-hook. The operation of coupling is further insured by a guide projecting over the 15 coupling-hook at a sufficient distance therefrom to allow the outer end of the outer link of the chain to pass into engagement with the coupling-hook. The links of the coupling-chains are so constructed and sustained that 20 they support each other in a horizontal line stiffly prior to the coupling action. The draw-hook is carried upon a shaft which also passes through the draw-bar, and this shaft is provided with handles at either end, so that the 25 hook can be turned round into the position for either coupling or uncoupling, or for placing the hook, with its tail-piece of either of two adjacent couplings, into such position as will allow either of the coupling-chains to be 30 coupled with the opposite draw-hooks. The apparatus is provided with catches or locks 35 for securing the draw-hook and its connections in either of the positions hereinbefore mentioned. A rest is or may be provided for 40 the outer link of the coupling-chain on one or both sides of the draw-hook. The lock of the apparatus is so constructed that a cam or its equivalent on the aforesaid shafts, as the shafts are rotated, both locks and unlocks the 45 draw-hook, and at the same time moves the draw-hook into any one of its required positions.

In the drawings, Figure 1 is a plan, and Fig. 2 a side elevation, of a railway-coupling 50 as constructed according to my present invention. Figs. 3 and 4 are side elevations of the

same when respectively in its coupling and uncoupling positions. Figs. 5, 6, 7, and 8 are enlarged views of detached portions of the same, and all hereinafter more particularly 55 described. Fig. 9 is a plan, drawn to a reduced scale, of a pair of couplings as constructed according to my present invention when in their engaged or coupled position. Figs. 10, 11, and 12 are side elevations of a 60 modified portion of the same when in positions differing, all as hereinafter more particularly described.

In carrying my present invention into practice I construct the outer link, *a*, of the coupling-chain with the guides *b*. These guides are so arranged that upon any two railway-vehicles fitted with my improved coupling apparatus approaching each other the outer link, *a*, of either one of such vehicles, as may be desired, 70 is guided up the tail-piece and over the point *c* of the opposite coupling-hook, *d*. The inner link of the coupling-chain is composed of the two parallel bars *e*, which bars are riveted, as shown at *f*, or otherwise suitably secured 75 together at their inner ends. The rivet or pin *f* passes through the slotted hole *g* of the coupling-hook *d*, and is constructed in such a manner as admits of the coupling-chain pivoting 80 freely in the said slotted hole. The outer ends 85 of the bars *e* are secured to the inner ends of the coupling-link *a* by means of the screwed bolt and nut *h*, or their equivalents, provision being had for the free radial motion of the said link *a* about the pivot *h* in an upward direction. The outer link, *a*, may be rigidly supported in a horizontal or approximately horizontal position by the inner link, *e*, for which purpose the bars of the said link *e* are provided with the projections *i*, arranged in such 90 position as to obstruct the radial path of the stops *j*, formed on the outer link, *a*. The inner link, *e*, when in this coupling condition, is supported by the pin *k*, which rests upon the latch *l*. This latch *l* is pivoted at *m* to the 95 lower part of the coupling-hook *d*, and is so arranged relatively with the adjacent parts thereof that it abuts at its top against the said coupling-hook when supporting the link *e*, but can be turned about its pivot *m* in such manner 100 that the curved slot *n* is left clear. The curved slot *n* is formed in the lower part of the coup-

ling-hook *d*, and is of width sufficient to allow the pin *k* to be pushed over the point of the latch *l*, so as to be clear of the said latch. The coupling-hook is carried upon the transverse bar *o*, which, as shown on a reduced scale at Fig. 9, extends outward to the two sides of the vehicle and at its extremities is squared, so as to admit of the hand-levers *p*, or their equivalents, being placed thereon when required for the purposes of coupling or uncoupling. The transverse bar *o* is supported in the sides *q* of the forked end of the bar *r*, this bar being connected to the draw-bar of the vehicle in any of the well-known ways. The transverse bar *o*, which is or may be also supported at or near its ends in suitably-slotted brackets or their equivalents, is provided with the key or feather *s*, (represented in dotted lines upon the annexed) drawings, and which is capable of being turned rotatively for a slight distance in the coupling-hook *d* without affecting its position, this turning motion being employed to operate the locking mechanism. This locking mechanism consists of the two cams *t*, which fit tightly upon and rotate always with the shaft *o*, and of the cam-piston *u*, which is operated by the cams *t*, the said cams being arranged one at each side of the coupling-hook, as represented in dotted lines at Fig. 1. The cam-piston *u* is represented in enlarged view in side elevation at Fig. 5, and in front elevation at Fig. 6, while one of the cams *t* is represented, also on an enlarged scale, in side elevation and in front elevation or edge view at Figs. 7 and 8, respectively. The coupling-hook is provided with the projections *v*, one of which, according to the position in which the said coupling-hook *d* is locked, is engaged by the recess *w* in the face of the cam-piston *u*, as shown more particularly at Figs. 5 and 6. The cam-piston *u* is pressed outward by means of the spiral or equivalent spring, which is represented in dotted lines at *x* upon the annexed drawings, and which is contained within a recess formed in the bar *r*. The forked end *q* of the bar *r* is closed in at its top by the sheet-iron casing *y*, and the upper projections, *z*, of the said bar *r* serve to direct the outer end of the outer link, *a*, of the opposite coupling down over the point *c* of the coupling-hook, while the lower projections, *a'*, serve to support the said link *a*, so as to pass over the point *c* when uncoupling, as is shown at Fig. 4 of the annexed drawings, in which figure the link *a* is represented in dotted lines.

Should it be desired to couple together two railway-vehicles each fitted with my improved coupling, the links *a* at the time hanging loose in a vertical position, as indicated in dotted lines at Fig. 2, one of the coupling-hooks *d* is turned into the position indicated at Fig. 3, and the other of the two coupling-hooks is turned into its lowermost position, as represented at Fig. 4, where the latch *l* by its own gravity pivots so that its point projects into the curved slots *n* and engages with the pin *k*,

and in being raised the coupling-hook *d* carries the coupling-chain upward with it into the position shown at Fig. 2. The two vehicles, with their couplings so arranged, are run toward each other, and on meeting the outer link, *a*, of the horizontal coupling-chain runs, in the manner indicated in dotted lines at Fig. 3, up the tail-piece and inclined back of the opposite coupling-hook, and on striking against the fork *q* or projections *z* pushes the said engaging coupling-chain back, and thereby disengages the pin *k* from the latch *l*, and thus the link *a* falls down into the hook *d* and completes the coupling operation.

For uncoupling two such railway-vehicles, the engaged coupling-hook *d* is simply turned over into the position indicated at Fig. 4, when the chain by its own gravity falls over the point *c* of the said hook; or the disengaged coupling-chains may be raised into a horizontal or coupling position by the apparatus represented, respectively, in side elevation at Figs. 10 and 11, and in part side elevation and part vertical section at Fig. 12 of the annexed drawings. The coupling-hook *d* under this construction carries the forked lever *b'*, or its equivalent, which is pivoted at *c'* to the said hook. The rivet or pin *f*, as shown more particularly in section at Fig. 12, is flattened on two sides at that part of its length which is opposite to the lever *b'*. The distance between the two arms *d'* of the lever *b'* is such that it admits of the flattened portion of the pin *f* falling between the said arms, as indicated at Figs. 10 and 12. The upper part of the lever *b'* is provided with the stop *e'*, which abuts against the front of the coupling-hook *d* when the said lever *b'* is in that position necessary to receive the pin *f*. When the coupling-hook *d* is turned down, as indicated at Fig. 12, for the purpose of raising the coupling-chain to a coupling position, the lower end of the lever *b'* is brought against the rigid stop *f'*, or its equivalent, which projects from the under side of the fork *q* or other convenient part, and thus forces the said lever *b'* into such a position that the pin *f* drops between the arms *d'*, and thus the coupling-chain may be raised into its coupling position—that is to say, into the position represented at Fig. 10 of the annexed drawings.

It is obvious that when the coupling-chain is forced backward by any colliding vehicle or other structure the pin *f* is disengaged from the lever *b'*, which then by its own gravity cant over into an inoperative position, as shown at Fig. 11 of the annexed drawings.

I claim—

1. The combination of a draw-bar, a hook pivoted to the draw-bar, a link hinged to the hook, means for locking the hook in required position, and a latch or lever for supporting the link on the hook, substantially as set forth.

2. The combination of a draw-bar, a hook, *d*, having projections *v* on its rear edge and pivoted to the draw-bar, a piston located in line with the draw-bar at the rear of the hook,

125

130

- and having a recess, *w*, for receiving the projections, and a spring for projecting the piston, substantially as set forth.
3. The combination of a draw-bar, a hook, 5 *d*, having projections *v*, a shaft having cams *t*, and a spring-pressed piston having a recess, *w*, for the projections, substantially as set forth.
4. The combination of a draw-bar, a hook, *d*, pivoted therein, formed with curved slot *n* 10 and a latch, *l*, and a link hinged to the hook having a pin, *k*, engaged by the latch, substantially as set forth.
5. The combination of a draw-bar, a hook pivoted thereto having elongated slot, a link 15 pivoted in said slot, and means for supporting the link in horizontal position on the hook, substantially as set forth.
6. The combination of a draw-bar, a hook pivoted thereto, and a chain pivoted to the 20 hook, consisting of bars *e*, having projections *i*, link *a*, having stops *j*, pivot-pin *f*, and bolt *h*, substantially as set forth.
7. The combination of a draw-bar, a hook pivoted thereto, and a link, *a*, having guides *b* and hinged to the hook, substantially as set forth. 25
8. The combination of a draw-bar having a forked end, *q*, projections *z z*, and casing *y*, and the hook *d*, pivoted to the end, substantially as set forth. 30
9. The combination of a draw-bar having projections *z z* and link-rests *a' a'*, and the hook *d*, pivoted to the draw-bar, substantially as set forth.

In testimony whereof I have signed my name 35 to this specification in the presence of two subscribing witnesses.

JOHN DARLING.
